UNITED STATES PATENT OFFICE.

THOMAS THOMAS, OF CARDIFF, COUNTY OF GLAMORGAN, ENGLAND.

MACHINE FOR LIFTING OR HOISTING.

SPECIFICATION forming part of Letters Patent No. 293,114, dated February 5, 1884.

Application filed November 30, 1883. (No model.) Patented in England April 28, 1883, No. 2,162.

To all whom it may concern:

Be it known that I, THOMAS THOMAS, a subject of the Queen of Great Britain, residing at Cardiff, in the county of Glamorgan, England, manufacturer, have invented certain new and useful Improvements in Machinery for Lifting or Hoisting, (for which I have received Letters Patent in Great Britain, No. 2,162, dated April 28, 1883,) of which the following is a specification.

My invention relates to those parts of machinery for lifting or hoisting by which the arresting, starting, and reversing of the motion of the machinery are effected; and my said invention consists of the construction and combination hereinafter described of the parts of an adjustable belt-shifter for shifting the driving-belts from the fast to the loose pulleys of the driving mechanism, or the reverse; and, also, of the construction and combination hereinafter described of the parts for operating the belt-shifter, and, also, of automatic stopping-gear for arresting the motion of the machinery at the proper times.

Figure 1 of the accompanying drawings represents in side elevation, Fig. 2 in plan, and Fig. 3 in end elevation, machinery for lifting or hoisting containing my improvements. Fig. 4 represents a portion of Fig. 1, and Fig. 5 a portion of Fig. 2, drawn to a larger scale. Fig. 6 represents the belt-shifting bar and parts connected with it, drawn to the same scale as Figs. 4 and 5; and Fig. 7 represents one of the belt-shifting forks and one of the fixing-brackets of the belt-shifting bar.

The same letters of reference indicate the same parts in the several figures of the drawings.

The belt-shifting mechanism and the automatic gear are shown in connection with a hoisting-machine where two driving-belts, one being crossed, as usual, are used, one belt being used for raising and the other belt for lowering the load, the said two driving-belts being employed in connection with two loose and one fast pulley.

I will first describe the adjustable driving-belt shifter and parts connected with it.

c is the belt-shifting bar carrying the belt-shifting forks *ff*, the said bar *c* being situated parallel to the pulley-shaft *p*, carrying the fast

pulley *p* and the loose pulleys *p' p'*. The said belt-shifting bar *c* has a longitudinal to-and-fro motion given to it in the manner hereinafter explained. The said bar *c* is square through the greater part of its length; but the end *d* is cylindrical, and a quick-threaded screw is cut upon it. Upon the square part of the bar *c* the belt-shifting forks *ff* are fitted, being secured thereon by set-screws, as represented in Fig. 6. The belt-shifting bar *c* is supported in adjustable brackets or bearings *b b'*, one at each side of the machine. The brackets *b b'* work in semicircular slotted seats at *a a'*, made in the frame-plates *k k*, supporting the pulley-shaft *p*. The said semicircular slotted seats *a a'* are concentric with the pulley-shaft *p*, as seen in Fig. 4, and in the said slotted seats the brackets *b b'* may be adjusted. The slotted seats *a a'* consist of a semicircular slot, *a*, at the sides of which facings *a'* are made. In the slot *a* the middle of the bracket fits, and the curved flanges of the bracket work upon the facings *a' a'* of the slot. The brackets are secured in the slots *a* of the slotted seats by means of the screw bolts and nuts at *b' b'* and plates or glands *c' c'*, the flanges of the brackets and plates or glands clipping and traveling on the parts *a' a'* of the seats.

The construction of the adjustable brackets will be best understood by referring to the enlarged views, Figs. 4, 5, 6, and 7. In securing the two brackets *b b'* in their places, they are fixed opposite one another or in the same line, so as to secure the belt-shifting bar *c* in a horizontal position. By moving the brackets *b b'* in their semicircular seats *a a'*, the said brackets can be adjusted with great nicety to suit the inclination of the driving-belts carried by the forks of the said bar. The adjustable bracket *b'* at one side of the machine is plain, and has a square hole made in it, which receives the square end of the belt-shifting bar *c*, the said bar being by this means prevented from rotating. The adjustable bracket *b* at the other side of the machine has a jaw, *b'*, attached to it, between the fork of which jaw a pinion, *e*, is fitted. The bush of this pinion *e* is screwed and works upon the screwed end *d* of the belt-shifting bar *c*. By means of the jaw *b'* of the bracket *b*, the pinion *e* is prevent-

ed from traveling laterally. Gearing with the pinion e is a spur-wheel, g , which works loosely upon the projecting end of the pulley-shaft p , or on a cylindrical prolongation of the bearing in which the shaft p revolves. By an examination of the drawings it will be seen that the pinion e will always be in gear with the spur-wheel g , in whatever position the adjustable brackets b b' may be fixed in the slotted 10 seats a a' .

On the outer face of the spur-wheel g is a sheave, h . A rope for operating by hand the belt-shifting mechanism is attached to the sheave h , which rope is usually carried through 15 all the floors of the building, as shown at r' , but may be elsewhere conducted as required. By moving the said rope r' attached to the sheave h backward or forward, the spur-wheel g is made to rotate, and with it the pinion e on 20 the screwed end d of the belt-shifting bar c , and the said pinion, acting as a screw-box, and having only a rotary motion, causes a longitudinal motion in one or other direction to be given to the belt-shifting bar c . By the traversing motion of the belt-shifting bar c in one 25 direction, its forks f f are made to transfer one of the driving-belts from the fast pulley p^2 to one of the loose pulleys p^3 , so as to arrest the motion of the machine, the further motion of 30 the bar c in the same direction starting and reversing the motion of the machine by bringing the other or cross belt from the loose pulley, on which it rested, onto the fast pulley p^2 . The same action takes place when the bar c is 35 moved in the other direction. When it is required to entirely stop the machine, the rope on the sheave h is so pulled as to bring the forks f f into the position represented in the drawings, and thereby place both the driving- 40 belts onto the loose pulleys p^3 p^3 . The gearing is generally proportioned so that from three to four feet pull of the rope is necessary to produce a travel of the bar c sufficient to shift one belt off the fixed pulley and the other belt onto the fixed pulley, for reversing the motion of the hoist, the stopping of the hoist being effected by bringing the said rope into an intermediate position. The pinion e , when at rest, acts as a lock-nut upon the bar c , and 45 by preventing its longitudinal motion effectually preserves the driving-belts in the positions to which they have been brought by the actuating-rope attached to the sheave h . When the belt-shifting mechanism is used without 50 the automatic gear hereinafter described, stops are fixed on the belt-shifting bar c , to limit its to-and-fro motion. When pulleys of larger or smaller diameter than those represented are used in hoisting-machines, the slotted seats 55 a a' of the adjustable brackets b b' have the required radius given to them, and the diameters of the pinion e and spur-wheel g are arranged accordingly.

I will now describe the automatic gear, constructed according to my invention, for working the belt-shifter and arresting the motion of the machinery.

q is the winding-drum, the shaft z of which is prolonged beyond one of its bearings. The prolonged part of the shaft is marked z' , and 70 is screwed with a fine screw-thread. On the said screwed end z' of the drum-shaft z a sheave, y , having a screwed bush, has a traversing or longitudinal motion. The said sheave y works between a fixed collar or nut, x , and the adjustable nuts w , which latter may be locked 75 in any required position on the screwed part z' of the shaft z . When the traversing drum-shaft sheave y reaches either the collar x or the adjustable screw-nuts w , it has a rotary 80 motion communicated to it, which is transmitted by the rope r to the sheave h on the pulley-shaft p . The rope r may be an endless one, or a rope may be coiled on the sheave h , and, after being coiled on the sheave y , may 85 be conducted through all the floors of the building, or elsewhere conducted, the rope at r^2 passing from the sheave y , replacing that marked r' , which was described as being connected to the sheave h in explaining the belt-shifting mechanism, and which last-named rope on the sheave h was used for reversing 90 and stopping the machinery by hand.

The action of the automatic gear is as follows: When the hoisting machinery is fixed 95 for use, the screw-nuts at w are locked in such a position on the screwed end z' of the drum-spindle that the sheave y , in traveling from the collar x to the nuts w , will make as many rotations as the drum-shaft does in winding a 100 load from the bottom of the building to the top. Supposing the drum-shaft z turns from right to left for raising the load, and that the thread on the screw z' is right-handed, the sheave y will be situated at the screw-nuts w 105 when the load is at the bottom of the building, and on the drum-shaft rotating in the direction indicated the drum-shaft sheave y , being held stationary by its rope r and acting as a screw-box, slowly advances inward upon the screwed end z' of the drum-shaft, and when the load has been raised to the required height the said sheave y abuts against the collar x on the shaft y' . The sliding motion of the sheave 110 y being now arrested, it partakes of the rotary motion of the drum-shaft, its rotary motion being transmitted through the rope r to the driving-shaft sheave h , the motion of which is transmitted through the spur-wheel g and pinion e to the belt-shifting bar c , and the driving-belt on the fast pulley p^2 is moved onto 115 one of the loose pulleys p^3 , and the hoist comes to rest.

For the purpose of restarting the hoist and reversing its motion, the attendant pulls the 120 rope at r^2 in such a direction as will give rotation to the drum-shaft sheave y , and through it to the pulley-shaft sheave p , in the same direction as that by which the hoist was brought to rest. The motion thus given to the sheave y slightly separates it from the collar x , as well 125 as moves the belt-shifting bar c ; this further motion of the said bar moving the other belt from one of the loose pulleys onto the fast pul- 130

ley, thereby starting the hoist in a reverse direction, the other belt remaining on the loose pulley, onto which it was transferred for stopping the hoist. As the drum-shaft z now rotates in an opposite direction to that first described, the drum-shaft sheave y retires from the collar x and now moves outward upon the screwed end z' of the drum-shaft z , and on the load descending to its full extent the sheave y reaches the screw-nuts w , when, its sliding motion being again arrested, it partakes of the rotary motion of the said drum-shaft, which motion being transmitted through the rope r , sheave h , and gearing $g\ e$ to the belt-shifting bar c , a return traversing motion is given to the said bar c , and the hoist is brought to rest, restarted by hand, and the motion reversed, as hereinbefore described. It will thus be understood that so long as the drum-shaft sheave y is traversing between the collar x and the screw-nuts w on the screwed end of the shaft the belt-shifter is inoperative, except by hand; but as soon as the said sheave y reaches either the screw-nuts or the collar rotatory motion is communicated to it, and the belt-shifter is operated upon and the machine brought to rest, the restarting of the machine being effected by hand, as before explained. By adjusting the position of the screw-nuts w on the screwed end of the drum-shaft, the arresting of the motion of the hoist, when the load has reached the desired height or has descended the required distance, can be determined with great nicety.

35 The belt-shifter hereinbefore described and illustrated may be used apart from the automatic stopping-gear hereinbefore described and illustrated.

When the first motion-shaft of a hoisting machine is worked direct from the cylinder of an engine, instead of having the power conducted thereto by belting, the automatic arrangement on the winding-drum shaft and its connections may be used apart from the belt-shifter hereinbefore described and illustrated for the purpose of regulating at suitable times the driving-power. In this case the sheave y is geared by a rope or other gearing to the engine by which the hoisting-machine is worked.

I have shown at s , Fig. 2, in combination 50 with the hoisting-machine, self-sustaining gear; but as the self-sustaining gear constitutes no part of my invention I do not think it necessary to describe the same.

Having now described the nature of my invention and the manner in which the same is to be performed, I wish it to be understood that I claim as my invention of improvements in machinery for lifting or hoisting—

1. The combination of the pulley-shaft, the 60 brackets adjustable in the slotted seats, the belt-shifting bar having its bearings in the said brackets, and the belt-forks connected to the shifting-bar, substantially as and for the purpose set forth. 65

2. The combination of the screw-threaded shifting-bar, a supporting-bracket therefor, the pinion working on the threaded portion of the shifting-bar and inclosed in the supporting-bracket, the pulley-shaft, and the loose 70 pinion and sheave connected with the pulley-shaft, substantially as and for the purpose set forth.

3. The combination of the drum-shaft having a portion thereof screw-threaded, the 75 sheave traveling on the threaded portion thereof, the screw-nut and collar on opposite sides of the said sheave, the pulley-shaft with the sheave and pinion thereon, means for connecting the two sheaves, the screw-threaded belt-shifting bar and the belt-forks connected thereto, and the pinion working on the threaded portion of the shifting-bar and meshing with the pinion on the pulley-shaft, substantially 80 as and for the purpose set forth. 85

4. The combination of the drum-shaft having a portion thereof screw-threaded, the sheave traveling on the threaded portion thereof, and the screw-nut and collar on opposite sides of the said sheave, substantially as and for the 90 purpose set forth.

THOMAS THOMAS. [L. S.]
